SELF-PROPELLED LOADING DEVICE

James L. Juhl and Lyle H. Tufty, both of Hudson, Iowa
Filed Mar. 29, 1965, Ser. No. 84,470

Term of patent 14 years

(Cl. D14—3)

Fig. 1

Fig. 2

Fig. 3

FIG. 1 is a side elevational view of a self-propelled loading device showing our new design;

FIG. 2 is a top plan view;

FIG. 3 is a perspective view taken from the left rear side;

FIG. 4 is a perspective view taken from the right front side;

FIG. 5 is a side elevational view when the lifting arms are in a lowered position; and

FIG. 6 is a perspective view taken from the right front side with the lifting arms in a lowered position.

The dominant features of our design are shown by the solid lines.

The characteristic features of our design reside in the upstanding posts at the rear in combination with the

tapered boom arms, gusset plates, and depending arms connected to the bucket as shown.

We claim:

The ornamental design for a self-propelled loading device, substantially as shown and described.
